Filed Mar. 7, 1969, Ser. No. 16,119

Term of patent 14 years

Int. Cl. D21—01

U.S. Cl. D34—5

FIG. 1 is a perspective view of a game board embodying my new design;

FIG. 2 is a plan view of the same;

FIG. 3 is a side elevational view of the same;

FIG. 4 is a front end elevational view of the same; and

FIG. 5 is a rear end elevational view of the same.

An elevational view of the side opposite that shown in FIG. 3 is essentially a mirror image thereof.

I claim:

The ornamental design for a game board, as shown and described.
